UNITED STATES PATENT OFFICE.

HENRY BARRY, OF JAMESTOWN, NEW YORK, ASSIGNOR OF ONE-HALF TO CHARLES J. C. SCHOLPP, OF JAMESTOWN, NEW YORK.

GLUING-CLAMP.

1,283,393.

Specification of Letters Patent. Patented Oct. 29, 1918.

Application filed March 8, 1918. Serial No. 221,119.

To all whom it may concern:

Be it known that I, HENRY BARRY, a citizen of the United States, residing at the city of Jamestown, in the county of Chautauqua and State of New York, have invented certain new and useful Improvements in Gluing-Clamps, of which the following, taken in connection with the accompanying drawings, is a specification.

10 The invention relates to gluing clamps for veneer and the improvement consists in providing means for clamping the glue coated sheet veneer around columns, posts and similar bodies whose circumferential surface 15 or a portion thereof it is desired to cover with veneer, and to insure holding the abutting edges of said veneer in alinement while making a perfect contact over the remainder of the veneered surface; and the invention consists in the novel features and 20 combinations hereinafter set forth and claimed.

In the drawings, Figure 1 is a perspective view of the clamp showing the bolts for drawing the parts together, the clamping fabric not being shown. Fig. 2 is a plan view of one of the stiffening bars. Fig. 3 is a sectional view at line 3—3 in Fig. 1 showing the construction and arrangement 30 of the parts with the clamping fabric in position and a portion of the column or post or other body with the veneer clamped thereon. Fig. 4 is a crosswise sectional view of a modification of the clamping joint for the 35 flexible fabric. Fig. 5 is an end elevation of the clamp with a round body in position and the veneer clamped thereon showing a modification from the preferred form shown in Figs. 1 and 2. Fig. 6 is a top plan view 40 of the gluing clamp showing the construction and arrangement of the different parts with the lengthwise central joint; and Fig. 7 is a side elevation of the gluing clamp with the round body held therein showing the 45 construction and arrangement of the holding bracket for the bolts and cross bars. Fig. 8 is a plan view of the under side of the different parts of the top portion of the clamping mechanism separated partially 50 from one another to show the construction and arrangement of the same; and Fig. 9 is a sectional view at line 9—9 in Fig. 8 showing the form and arrangement of said parts.

Like characters of reference refer to corresponding parts in the several views.

The numeral 10 designates the post, column or other body to be veneered which may be round, elliptical or other shape in cross section, and the numeral 11 the veneer 55 for covering the same which may be in one strip or a plurality of strips. The numeral 12 designates the clamping fabric which is preferably some form of strong flexible fabric like canvas, duck or some equally 60 strong material which is capable of resisting heavy strains.

The numeral 13 designates one of the clamping plates for holding and binding the fabric 12 around the body 10, and the 65 numeral 14 designates the other clamping plate. The adjacent edges of said plates 13 and 14 are preferably arranged with a straight edge and an angular flange edge 15 which overhangs the straight edge of the 70 plate 14 so as to clamp and hold the flexible material 12 firmly in position over the lengthwise joint 30 in the veneer 11. For certain purposes the modification shown in Fig. 4, in which both edges of plates 13 and 75 14 are straight and flat would serve a good purpose, but the overhanging edge flange 15 is usually preferred as it makes a stiffer closer joint.

The cloth or fabric 12 is firmly attached 80 in position over said adjacent edges of the plates 13 and 14 by means of the plates 16 and 18 which are bent around said edges in lengthwise flanges to hold the cloth or other 85 flexible material firmly in position thereon. 90 The edge 17 of the attaching plate 16 is bent in the same shape as the edge 15 of the plate 13 to fit over the same. The fabric attaching plates 16 and 18 are held in position upon the edges of the plates 13 and 14 by means 95 of latches 19 and 20 which engage over the bolts 21 and have lock nuts 22 thereon to hold said latches 19 and 20 firmly in position when once turned into latching engagement on said bolts 21. The latches 19 and 100 20 are pivotally attached at 23 and 24 to the clamping plates 13 and 14 as shown in the plan view of the under side in Fig. 8.

In order to set or stretch the cloth 12 around the veneer on the body to be veneered, the bolts 31 are provided which are engaged in slotted brackets 25 and 26, which slotted brackets 25 and 26 are supported, a

spaced distance above the plates 13 and 14 to slidably receive thereunder the stiffening bar 28, supporting sleeves or tubes 27 being provided on spaced bolts 21 underneath said brackets 25 and 26 to give the spaced distance required between the plates 13 and 14 and the brackets 25 and 26 in order that said stiffening bar 28 may be slipped under the brackets 25 and 26 and hold firmly upon the plates 13 and 14 and particularly upon their central portion at the joint 30. The angular flange portion 15 is preferably notched as shown at 29 to receive the stiffening bar 28 through said notch 29 and thus 15 fold flat against the top of the plates 13 and 14, though the spring sleeves 27 may be made of greater length and thus space the brackets 25 and 26 farther above the top of the plates 13 and 14 so that said stiffening bar 28 may pass through and hold firmly on the top of the angular portions 15-17 at the joint 30, as shown in the modified form in Figs. 3 and 5.

The clamping bolts need not be in combination with a stiffening bar 28, but the bolts may be arranged with slotted brackets 34 and 35 and a bolt 33 spaced between said bolts 31. It is obvious that the bolts 31 and 33 should be placed sufficiently close together to hold the two plates 13 and 14 firmly in position so that they cannot spring or permit the fabric 12 to be relaxed in any degree from its clamping hold upon the veneer 11 on the body 10.

It is also obvious that the lengthwise edges of the veneer 11 at the joint 30 will be the hardest portions of the veneer to hold in place and cause to adhere perfectly. Accordingly, the stiffening bars 28 are provided at sufficiently close intervals to give great rigidity to the holding power of the clamping plates 13 and 14. In order that said joint 30 may be held still more firmly and also in order that the body 10 with the veneer 11 and fabric 12 thereon be held firmly in line, a support 36 is provided which is preferably hollowed and upon which said body 10 with the veneer and fabric 11 and 12 rests either at intervals or throughout 45 its length. The ends or sides of the supporting element 36 are slotted as shown at 37 to receive therein the bolts 40, the lower end of the slot being under cut as shown at 38 to receive the nut 39 of said bolt 40. The open ended slots 41 are provided in the ends of the bars 28 in order to receive the upper ends of the bolts 40 so that said bolts 40 may be easily inserted and held in place.

In using the clamp a body 10 is provided, which may be a post or column of any desired shape around which the veneer 11 may be wrapped, as for example, round, elliptical, hexagonal or other shape, so that the fabric 12 draws freely around said body

without displacing the veneer. A strip or strips of the veneer 11 sufficient to cover the surface to be veneered is coated with glue and the body 10 placed thereon upon the fabric 12 on the support 36, the edges 70 of the veneer 11 being trimmed to make a close joint at 30 along said body 10 when the veneer 11 extends entirely around said body. The fabric or cloth 12 is then folded around the clamping plates 16 and 18 so as 75 to exactly meet at joint 30 and said plates are latched onto the edges of the plates 13 and 14 in position for clamping the cloth 12 around the body 10. The stiffening bars 28 are then inserted to hold the plates 13 and 80 14 in line with pressure at the joint 30. The bolts 31 are then inserted and tightened, the plates 13 and 14 slipping on the bars 28 until they hold the clamping fabric 12 firmly in position around the veneer body 10, after 85 which the bolts 33 are inserted. The fabric 12 is pressed down upon the veneer joint 30 by the bars 28 on plates 13 and 14 so as to hold said veneer joint throughout its entire length in close adhesion to the body 90 10 along each side thereof. This is usually sufficient to hold the veneer along the joint 30 in perfect alignment.

In the case of badly warped or out of line veneer however it is sometimes necessary to 95 give special pressure to the joint 30 and the veneer each side thereof. Accordingly in such cases the bolts 40 are placed in the slots 37 in support 36 and in slots 41 in bar 28 and tightened, thereby drawing the bar 28 100 and plates 13 and 14 firmly down onto the veneer each side of the joint 30 pressing said veneer firmly into line and forcing it into correct position for a perfect joint.

I claim as new:—

1. A gluing clamp comprising movable clamping plates, mechanism to move said plates toward one another, flexible fabric attached to the edges of said plates to surround the body to be clamped, and removable bars crosswise of the joint between said plates to hold said joint in line.

2. A gluing clamp comprising movable clamping plates, spaced bars insertible crosswise of said plates to hold the joint 115 therebetween in line, means on said plates to move said plates toward one another on said crosswise bars, and clamping fabric attached to the adjacent edges of the joint thereof, said plates to draw said fabric 120 around the body to be clamped.

3. A gluing clamp comprising removably mounted spaced bars, plates slidably mounted on said spaced bars to move toward one another thereon, flexible fabric removably attached to the opposite inner edges of said plates to draw around the article to be clamped, and mechanism for moving said plates toward one another.

4. A veneer clamp comprising spaced 130

bars, plates slidably mounted on said spaced bars to move toward one another, flexible fabric removably attached to the adjacent edges of said plates to draw around the body to be veneered, mechanism for moving said plates toward one another, and means for pressing said bars on said adjacent edges of said plates.

5. A veneer gluing clamp comprising removable bars, movable clamping plates slidably mounted on said removable bars to hold the same in line, bolts removably mounted on said plates to draw the same toward one another, and flexible clamping fabric attached to the adjacent edges of the joint therebetween said plates to draw said fabric around the outer surface of the veneer by said bolts.

10. A veneer gluing clamp comprising spaced stiffening bars, plates slidably mounted on said stiffening bars, an inner flanged edge on one of said plates overhanging the adjacent inner edge of the opposite plate, flexible clamping fabric attached to said inner edges to clamp the veneer to the body to be veneered, and means to move said plates toward one another on said bars with holding pressure on said overhanging flange edge of one of said

15. plates.

20. 7. A veneer gluing clamp comprising

movable clamping plates having interfitting adjacent inner edges to firmly hold the joint therebetween, flexible fabric to clamp around the body to be veneered, similarly 35 shaped plates for attaching said fabric to said inner edges of said clamping plates, and bolts to draw said clamping plates toward one another.

25. 8. A veneer gluing clamp comprising 40 movable clamping plates, spaced stiffening bars crosswise of said clamping plates to hold the same, slotted brackets supported in spaced relation above said clamping plates, stiffening bars slidably received between 45 said brackets and said clamping plates to hold said plates against the body to be veneered, flexible material attached to said clamping plates by said removable attaching plates, attaching plates shaped to engage 50 around the opposite inner edges of said clamping plates lengthwise thereof to removably attach said flexible material to said clamping plates, and bolts received in said slotted brackets to draw said clamping 55 plates toward one another.

In testimony whereof I have affixed my signature in the presence of two witnesses.
